Primary Examiner — Cynthia Ramirez*Assistant Examiner* — Laura H Yu(74) Attorney, Agent, or Firm — Banner & Witcoff, Ltd.(57) CLAIM

The ornamental design for a shoe, as shown and described.

DESCRIPTION

FIG. 1 is a front perspective view of a shoe showing my new design; and,

FIG. 2 is a second front perspective view thereof. The even-length broken lines within the shaded areas represent stitching and form no part of the claimed design. The uneven-length V-shaped broken line within the shaded area represents a feature that forms no part of the claimed design. Additional uneven-length broken lines within the shaded area represent a zipper pull-tab and form no part of the claimed design. The uneven-length broken lines depicting the remainder of the shoe show features that form no part of the claimed design.
